EYE BENDING DEVICE

Edwin R. Goldfield and Robert J. Stava, University Heights, Ohio, assignors to Picker X-Ray Corporation, Waite Manufacturing Division, Inc., Cleveland, Ohio, a corporation of Ohio

Application May 27, 1944, Serial No. 537,576

6 Claims. (Cl. 140—104)

This invention relates to improvements in a machine for bending eyes or loops in the ends of stiff filaments, hereinafter referred to generically as wires.

An object of the present invention is to provide a machine which will quickly bend a substantially closed flat loop in the end of a stiff wire such as is often required for the attachment of electrical conductors to the usual binding post.

Among the objects of the present invention are to provide a device which operates very quickly and which is substantially fool-proof.

Another object of the invention is to provide a device which is readily adaptable for various diameters of wire and various diameters of the loop formed in the end of the wire.

Still another object of the invention is to provide a substantially circular loop in the end of a wire with means for centering the main portion of the wire adjacent the loop so that the main portion lies substantially on the extension of a diameter of the loop.

Other objects and advantages of the invention will be apparent from the accompanying drawings and specification, and the essential features will be summarized in the appended claims.

In the drawings:

Fig. 1 is a side elevational view of a device for carrying out our invention with parts broken away to more clearly show the construction;

Fig. 2 is a top plan view of the device of Fig. 1 showing the parts in position at the beginning of a loop-forming operation;

Fig. 3 is a view similar to Fig. 2 showing the parts in position at the close of a loop-forming operation;

Fig. 4 is a top plan view of one of the interchangeable elements which rotates while forming the loop in the end of a wire; and

Fig. 5 is a sectional view of the same taken along the line 5—5 of Fig. 4.

It should be understood that the machine about to be described may be operated by hand, by foot, or by any usual source of power, the form here shown being for illustrative purposes only.

In the device of Figs. 1, 2, and 3, a shaft 10 is rotatably mounted in a housing 11 and the means for rotation is provided by means of beveled gear 12, which is pinned to shaft 10 mating with beveled gear 13 which is pinned to shaft 14 which is also rotatably mounted in a portion of the housing 11. A crank arm 15 is pinned to shaft 14 and coacts with a link 16 which is attached to a treadle or the like so that oscillation may be imparted to shaft 14. Spring 17 provides means for returning the shaft 14 to its starting point after link 16 is released. Fixed to the upper end of shaft 10 so as to rotate with it is a gear 18. This gear meshes with gear 19 which is rotatably mounted at 20 in the housing 11.

Mounted on top of gear 18 is a rotatable ele-

ment or flat circular disc 21 which is preferably removably mounted on the gear 18 so that various elements 21 may be supplied interchangeably for acting on wires of different diameter. To this end the disc 21 is provided with a central post 22 having a lower portion 22a which fits slidably into a hole 23 in the center of gear 18. The upper end 22b of this post extends above the upper surface of disc 21 and forms the post about which the wire loop is formed. Positioned radially outwardly from center post 22 is a positioning or driving pin 24 which engages in a suitable opening 25 in disc 21 and the lower end of which also fits slidably into a hole 26 in gear 18. Thus when disc 21 is dropped into position on gear 18 as shown in Figs. 1, 2, and 3, the disc is firmly held for rotation with the gear but at the same time is readily removable for interchangeability.

Means is provided on disc 21 for gripping the extreme end of a wire so as to carry the same around post 22b upon rotation of gear 18 and disc 21. The gripping means here shown comprises a knife edge 27a on a block 27 which is fixed in position on the upper face of disc 21 as by means of suitable screws or bolts 28. The knife edge is directed toward the free end of wire 29 as best seen in Fig. 2 and, upon rotation of the disc 21 in the direction of the arrow shown in Fig. 2, the knife edge 27a slides toward the end of wire 29 until the rotating knife edge digs slightly into the surface of the wire whereupon the end of the wire is carried around the post 22b to form a loop 29a as shown in Fig. 3.

One of the reasons for providing interchangeable discs 21 is to give the proper clearance between the post 22b and the knife edge 27a for wires of different diameters.

Stop means is provided for limiting the amount which the free end 29b of wire 29 extends beyond post 22b when the loop-forming operation begins. For this purpose, stop member 30 is provided so arranged that it is moved out of the way after it has performed its function of properly locating the end 29b of a wire at the beginning of the loop-forming operation. The stop member here shown comprises a plate suitably secured by screws or bolts 31 to the hub 19a of gear 19. This plate extends radially outwardly from the axis of hub 19a and at its outer end has a flange 30a bent downwardly so as to just clear the disc 21 and to provide an abutment for the wire end 29b. This stop member 30 is carried by the rotation of gear 19 during a loop-forming operation from its position shown in Fig. 2 to its position shown in Fig. 3.

Means is provided for guiding the operator in placing the wire 29 for a loop-forming operation. In the present instance, a platform 35 is built above the top surface of the housing 11 to a point about level with the top surface of disc 21. At the proper point along this platform a

recess or groove is formed by securing blocks 32 and 33 to the platform 31. The face 33a of block 33 is substantially parallel to a line tangential to post 22b on the side thereof toward knife 27a in the position of the parts as shown in Fig. 2. This is so arranged that when the insulation of wire 29 is against the face 33a, the bare wire portion 29b is tangential to post 22b on the side thereof toward the knife edge.

Means is provided for insuring that disc 21 does not leave its position on gear 18 except when it is desired to change discs. For this purpose, the end 32a of the block 32 is arranged to overlie, without touching, the edge of disc 21 as shown in the various views.

If a loop were formed in the end of a wire by means of the apparatus thus far described, it would be a satisfactory loop for some purposes. However, in making electrical connections, it is often desirable and makes a neater looking job, if the main portion of the wire 29 is centered with reference to the circular loop 29a. Our improved device provides means for so centering the main portion of the wire. To the gear hub 19a is fixed an arm 34 preferably underneath the stop member 30 and secured by the same screws 31. At the outer end of this arm is carried a downwardly extending pin 34a which is carried by rotation of gear 19 counter-clockwise as viewed in Figs. 2 and 3 during a loop-forming operation, from the position of Fig. 2 to the position of Fig. 3. It will be noted in Fig. 3 that pin 34a has moved to a position where it forces the main portion of wire 29 adjacent the end of the loop 29a to such a position that the main portion of the wire lies on an extension of the diameter A of the circular loop 29a. At the same time this action of pin 34a on the wire substantially closes the loop 29a. This completes the bending operation, and upon release of link 16 the spring 17 returns the parts to the position of Fig. 2 whereupon the loop 29a may be lifted off the post 22b and another wire inserted for a like operation.

A number of discs 21 may be kept on hand having suitable spacings between post 22b and knife edge 27a to accommodate wires of different diameters, and these discs are easily interchangeable by removing the screws which hold block 32 on platform 31 and moving the stop member 30 out of the way. Also, various post sizes 22b may be provided for loops of different diameters.

We have applied power means to our device by substituting a pinion for the beveled gear 12 and meshing the same with a power-driven rack, but, obviously, various means for driving the machine may be provided without departing from the scope of our invention.

What we claim is:

1. A wire bending device comprising a rotatable element, a post positioned axially of said element, a stop member spaced from said post for positioning the end of a wire lying on said element and substantially touching said post, a gripping member rigidly mounted on said element spaced from said post by more than the diameter of said wire, said gripping member having a sharp edge facing toward the end of said wire, and means for rotating said element in a direction to cause said gripping member edge to seize said wire and to carry the end thereof around said post forming a loop in the end of said wire.

2. The combination of claim 1 including means operative when said gripping member has carried the end of said wire a major portion of the way around said post for engaging the portion of

said wire near said loop and moving the same toward said free end of said wire and more nearly closing the loop.

3. A wire bending device comprising a rotatable element, a post positioned axially of said element, a stop member spaced from said post for positioning the end of a wire lying on said element and substantially touching said post, a gripping member rigidly mounted on said element spaced from said post by more than the diameter of said wire, said gripping member having a sharp edge facing toward the end of said wire, and means for rotating said element in a direction to cause said gripping member edge to seize said wire and to carry the end thereof around said post forming a loop in the end of said wire, said last named means including a rotatable gear beneath said element and interengaging formations on said gear and element spaced from the center of said gear and providing a positive drive between said gear and element.

4. In a device for forming a loop in the free end of a wire, a rotatable gear, a disc on the upper face of said gear, a central post upstanding from said disc, knife-edge means on said disc spaced from said post by little more than the diameter of a wire positioned tangentially of said post, the knife edge of said last named means being inclined toward the free end of said wire, stop means adjacent said post to limit the movement of the free end of said wire beyond said post, means for rotating said gear, a pinion meshing with said gear, and said stop means being carried by said pinion, whereby rotation of said gear and pinion carries said stop means away from the end of said wire.

5. In a device for forming a loop in the free end of a wire, a rotatable gear, a disc on the upper face of said gear, a central post upstanding from said disc, knife-edge means on said disc spaced from said post by little more than the diameter of a wire positioned tangentially of said post, the knife edge of said last named means being inclined toward the free end of said wire, stop means adjacent said post to limit the movement of the free end of said wire beyond said post, means for rotating said gear, said disc setting on said gear, interengaging post and recess means provided centrally of said disc and gear, and coaxing post and recess means eccentric of said disc and gear for driving said disc by rotation of said gear.

6. In a device for forming a loop in the free end of a wire, a rotatable gear, a disc on the upper face of said gear, a central post upstanding from said disc, knife-edge means on said disc spaced from said post by little more than the diameter of a wire positioned tangentially of said post, the knife edge of said last named means being inclined toward the free end of said wire, stop means adjacent said post to limit the movement of the free end of said wire beyond said post, means for rotating said gear, a pinion meshing with said gear, an arm carried by said pinion, and a pin on said arm in position to engage said wire at the base of said loop when rotation of said gear has caused said knife-edge means to carry the free end of said wire substantially around said post, said pin being moved by said arm to position where it causes the main portion of said wire to lie substantially on the extension of a diameter of said post.
